CLAIM

The ornamental design for a section of linear luminaire housing, as shown and described.

DESCRIPTION

FIG. 1 is a broken away bottom perspective view of a section of linear luminaire housing in accordance with our new design;

FIG. 2 is a broken away bottom plan view thereof; FIG. 3 is a broken away left side elevational view thereof, the right side elevation being a mirror image; and, FIG. 4 is a cross-sectional view thereof showing the uniform cross-sectional shape of the section of the housing illustrated FIGS. 1-3.

FIGS. 1-3 are broken away to indicate indeterminate length.
